M. Henderson

United States Patent Office.

MICHEAL HENDERSON, OF DETROIT, MICHIGAN.

Letters Patent No. 80,070, dated July 21, 1868.

IMPROVEMENT IN POTATO-DIGGERS.

The Schedule referred to in these Letters Patent and making part of the same.

TO WHOM IT MAY CONCERN:

Be it known that I, MICHEAL HENDERSON, of Detroit, in the county of Wayne, and State of Michigan, have invented a new and useful Improvement in Potato-Harvesting Machines; and I do declare that the following is a true and accurate description thereof, reference being had to the accompanying drawings, and to the letters of reference marked thereon, and being a part of this specification.

Figure 1 is a perspective view of my apparatus.

Figure 2 is a view of the same from the bottom.

The same letters indicate like parts in each figure.

The object I have in view in this invention is the construction of a simple, cheap, and effectual apparatus for digging and thoroughly cleaning potatoes preparatory to storing.

My apparatus is surmounted upon a proper frame and wheels, and is provided with suitable pulleys, to give motion to a series of brooms attached to endless chains, by means of which, after the potatoes have been taken out of the ground by a proper scoop, and delivered upon a longitudinal screen, the brooms are brought to work to clean the potatoes, and carry them to the rear end of the apparatus, while the dirt is dropped through the screen.

Having thus set forth the object of my invention, I will now describe its construction, and name its various parts.

A is an ordinary scoop, wide enough to take up any-sized hill of potatoes, as usually planted, and is secured to the front ends of longitudinal side-bars B, and grate-bars J, which are properly framed into and firmly attached to said side-bars B, the whole suspended by sufficient hangers, 2, to the side-timbers of the frame G at the rear end, and under the bars J and B are securely fastened to the bars B suitable runners, O, which may be provided with box-draws for receiving potatoes, if desired.

The frame G, carrying the apparatus, is surmounted upon the axle N, provided with wheels, D, supporting the rear end, while the front end rests upon any proper truck, like the forward truck of an ordinary wagon, provided with standards, L, and secured in a proper elevation by pins passing through the ends of the arms X and the standard L, as may be necessary.

The pulleys D, firmly secured to the axle N, near the outer sides of the frame-timbers G, give motion to the cylinder H by belts, F, passing around pulleys, E, secured to the cylinder H' by arms passing through the pulleys of the cylinder H', forming journals for the same.

The rear cylinder H is placed transversely at the rear end of the apparatus, and is properly journaled into the timbers G, and is operated by chain-belts I, to which are secured the transverse bars K, provided with brooms, brushes, or cleaners, 3, all of which is operated as follows:

By moving the apparatus forward, the wheels track in the furrows between the rows, the scoop A passes under the potatoes, which move back on to the front of the screen-bars J. The motion of the bars K being from front to rear over the bars J, and the brooms 3 being attached to the said bars K, the potatoes are carried back by the bars and brooms working from front to rear. The brooms traverse and work through and between the longitudinal bars J of the screen, clearing the same from vines or other foreign substances, and depositing the potatoes through the openings 4 in proper box-draws, if required.

To secure a greater amount of traction, the wheels D are provided with arms, M, having sharp projections inserted in their ends, preventing any slipping of the wheels in passing over the ground, and securing a continuous motion of the apparatus during its operation.

What I claim as my invention, and desire to secure by Letters Patent, is—

1. The scoop A, connected with the bars J and B, provided with transverse runners O, and openings 4, when arranged and operating substantially as and for the purposes set forth.
2. The cylinders H, bars K, and belts I, when operated by belts F from pulleys D, substantially as described, and for the purposes specified.
3. The combination of the above-named parts with frame G, bars K, brooms or brushes 3, secured to endless belts I, axle N, and wheels D, when constructed, arranged, and operating substantially as and for the purposes set forth.

MICHEAL HENDERSON.
